United States Patent Office.

L. H. BOWLUS, OF KNOXVILLE, TENNESSEE.

Letters Patent No. 67,944, dated August 20, 1867.

IMPROVEMENT IN FENCE.

The Schedule referred to in these Letters Patent and making part of the same.

TO ALL WHOM IT MAY CONCERN:

Be it known that I, L. H. Bowlus, of Knoxville, in the county of Knox, and State of Tennessee, have invented a new and improved Fence; and I do hereby declare that the following is a full, clear, and exact description thereof, which will enable those skilled in the art to make and use the same, reference being had to the accompanying drawings, forming part of this specification, in which—

Figure 1 is a side view of a portion of my improved fence.

Figure 2 is a detail horizontal section of a portion of the same, taken through the line x , x , fig. 1.

Figure 3 is a vertical cross-section of the same, taken through the line y , y , fig. 1.

Similar letters of reference indicate corresponding parts.

My invention has for its object to furnish an improved fence, adapted for use in places liable to be overflowed by high water, which shall be so constructed that the panels may be thrown down, so that the drift may pass over the fence without injuring it, and which can be set up again in a very short time; and it consists in hinging or pivoting the lower end of the central cross-bar or bottom of the panels to a short post, securely set in the ground; in securing the panels, when in a vertical position, by hooks or catches pivoted to the upper ends or parts of the short posts; and in connecting the ends of the adjacent panels to each other by keys or their equivalents, the whole being constructed and arranged as hereinafter more fully described.

A are the posts, which should be securely set in the ground, and which, for an ordinary fence, should be about two and a half feet high. B are the panels, the horizontal bars b^1 of which are connected to each other and secured in their proper relative positions by cross-bars b^2 placed upon each side of the ends of the horizontal bars b^1 , and by the cross-bars b^3 placed upon each side of the said horizontal bar b^1 , at the centres of the panels.

The fence is placed upon the down-stream side of posts A, and the lower ends of the outer central cross-bars b^3 are pivoted to the posts A a little above the surface of the ground, as shown in figs. 1 and 3, in such a way that the panels may be thrown down, so as to lie upon the surface of the ground, and so that, when down, they may swing laterally upon the said pivoting points.

C are hooks or catches, pivoted to the upper ends of the posts A, and which, when the panels are erect, pass between the horizontal bars b^1 , and hook or catch upon the central cross-bars b^3 of said panels, as shown in figs. 1, 2, and 3, and hold the panels securely in place. The ends of the panels are connected to each other by keys D, placed between the edges of the horizontal bars b^1 and between the end cross-bars b^2 of two adjacent panels, as shown in fig. 1. If desired, the ends of the adjacent panels may be connected by hooks, or in any other convenient and detachable manner.

By this construction, when the water rises, the panels may be disconnected, and allowed to fall down, so that the drift may pass over without injuring the fence. The fence need not be thrown down until the water has risen half way up the fence; then, by passing along in a boat, the panels may be readily thrown down. When the water has subsided, the fence can be readily and very quickly set up again.

I claim as new, and desire to secure by Letters Patent—

1. Pivoting or hinging the lower end of the central cross-bar b^3 to the lower part of the short post A, substantially as herein shown and described, and for the purpose set forth.

2. Securing the panels B, when in an erect position, by hooks or catches C, pivoted to the upper parts of the posts A, and taking hold of the central cross-bars b^3 of the said panels, substantially as herein shown and described, and for the purpose set forth.

L. H. BOWLUS.
